UNITED STATES PATENT OFFICE.

THOMAS ROBERT BEGGS, OF HARTFORD, CONNECTICUT.

FLUSH VALVE.

Application filed June 4, 1924. Serial No. 717,754.

To all whom it may concern:

Be it known that I, THOMAS R. BEGGS, a citizen of the United States, residing at Hartford, in the county of Hartford and

5 State of Connecticut, have invented a new and useful Flush Valve, of which the following is a specification.

This invention relates to flush valves, such as are adapted to be used in connection with 10 water closets and the like.

The primary object of the invention is to provide a valve of this type, which is efficient in its operation and yet has only a few parts and which may be manufactured 15 at a small cost, a valve which may be easily assembled, and in which worn out packing or other parts may be replaced with a minimum amount of labor and expense.

It is also an object of the invention to 20 provide a valve of this kind which does not begin to flush until the operating handle is released, so that the full pressure from the water main is exerted against the diaphragm until it is fully raised. This insures efficient 25 operation even where the pressure is low, and at each operation, the same amount of water will be discharged into the bowl.

The invention consists further in such 30 details of construction and combinations of elements as will be more fully explained in the following detailed description taken in connection with the accompanying drawings, which illustrate the preferred form of the invention.

35 In the drawings:

Figure 1 is a vertical section through the invention with the parts in normal or inactive position.

Figure 2 is a similar view of the valve 40 after the initial opening movement.

Figure 3 is a similar view showing the position of the parts during the flushing operation.

Figure 4 is a sectional view taken on the 45 line 4—4 of Figure 1.

Figure 5 is a sectional view taken on the line 5—5 of Figure 1.

Figure 6 is a sectional view taken on the line 6—6 of Figure 1.

50 Figure 7 is a fragmentary sectional view of the collar which supports the primary valve.

Figure 8 is a detail sectional view, magnified, of the hollow needle through which 55 water is slowly admitted to close the valve.

Figure 9 is a detail perspective view of the relief valve head.

Figure 10 is a perspective view of the collar.

Figure 11 is a perspective view of the primary valve head.

Figure 12 is a perspective view of the cage in which the sleeve valve reciprocates.

Referring in detail to the drawings, the invention is shown in connection with a 65 water supply pipe 1, and an outlet pipe 2 leading to the bowl. The valve is enclosed by a housing 3, having a laterally extending sleeve 4 threaded to the supply pipe 1, and having a downwardly extending outlet portion 5 terminating in a threaded nipple 6, which may be connected by the usual union 7 to the pipe 2.

The outlet portion 5 is extended upwardly within the housing 3 to provide a seat 8 75 for the outlet valve. The housing 3 is extended upwardly and terminates in a seat 9, externally threaded to receive a cap 10, which cooperates therewith to clamp a circular diaphragm 11. This diaphragm has 80 a circular central opening, which receives a collar 12 having a peripheral flange 13, which cooperates with a ring 14 threaded to the upper end of the collar to clamp the inner edge of the diaphragm 11, so that the collar is securely attached thereto.

The collar 12 has a downwardly extending reduced portion 15, which is internally threaded and receives a threaded boss 16, which forms an integral upward extension 90 of a cylindrical cage 17. The primary valve head 18 is circular and provided with a central opening 19 through which the boss 16 projects, and an annular shoulder 20, near the lower end of the reduced portion 15 of 95 the sleeve, cooperates with the upper surface of the cage 17 to clamp the valve head 18 to the cage. A suitable gasket 21 is carried by the valve head 18, and is adapted to cooperate with the seat 8 to form a water 100 tight closure.

The position of the primary valve head 18 is controlled by the position of the diaphragm 11, which in turn is determined by the total relative pressure on its upper and lower surfaces, respectively. When the water between the diaphragm 11 and the cap 10 is released, the pressure on the upper side of the diaphragm is relieved, and the diaphragm rises to open the valve 18. Dur- 110

ing the flushing operation, water is again slowly admitted to the space above the diaphragm through a bore 22 in the collar 12. The lower end of this bore is slightly contracted, so as to form a seat for receiving a needle 23, which has a restricted duct 24 therethrough. The needle 23 is preferably long enough so as to project slightly above the sleeve, so that it may be easily removed 10 for cleaning or substituting a needle having a larger or smaller duct. The under side of the flange 13 is formed with an annular shoulder 25, and the upper face of the valve head 18 is provided with a similar shoulder 15 26 of like diameter to receive a cylindrical screen 27 of fine mesh, which will aid materially in preventing the clogging of the duct 24.

The cage 17 is provided near its upper end 20 with ports 28, which are normally within the mouth of the outlet passage 5, but are uncovered when the valve 18 is raised to permit the water to flow therethrough, as seen in Figure 3. The ports 28, however, 25 may, under certain conditions, be closed from the inside, as hereinafter explained, by a sleeve valve 29, which is mounted to reciprocate within the cage 17. The lower end of the sleeve valve 29 is formed by a 30 spider 30, having openings 31 through which the water may pass.

The boss 16 is provided with a central bore 32, in which there is mounted for reciprocation a triangular stem 33, having its 35 upper end reduced and threaded to receive the head 34 of a relief valve. A gasket 35 is held between the head 34 and the shoulder formed at the upper end of the stem 33, and seats on the upper end of the boss 16. The 40 lower end of the stem 33 is also reduced and threaded, as at 36, and extends through the center of the spider 30, being held therein by a nut 37, which is so adjusted that the stem 45 has a limited reciprocatory movement in the spider. An expansible coiled spring 38 surrounds the stem 33 between the upper end of the cage and the spider 30, so that the latter is normally held at the lower end of the stem.

50 Since the stem 33 is triangular in cross section, it leaves a passageway 39 between it and the wall of the bore 32, and as soon as the relief valve head 34 is raised, as indicated by dotted lines in Figure 2, the water 55 confined above the diaphragm 11 is released, so that the pressure beneath the diaphragm overcomes the pressure on its upper face, and the primary valve 18 is opened. The lower end of the cage 17 is internally threaded, and receives a retaining ring 40. A circular 60 tilting head 41 is contained between the ring 40 and the lower end of the cage 17, the hub 41^a of the tilting head being disposed so as to give clearance to the lower end of the stem 33. A stem 42 projects downward-

ly from the hub 41^a, and is engageable by a laterally reciprocable plunger 43 to tilt the head 41, as shown in Figure 2, and to raise the cage 17. The plunger 43 is advanced in the usual manner by the depression of a 70 handle 44.

The operation of the valve will now be described. Normally, the parts are in the position shown in Figure 1. The water under pressure within the housing 3 is in 75 free communication through the hollow needle 23 with the space above the diaphragm 11. There is downward pressure, therefore, throughout the entire upper surface of the diaphragm, while the upward pressure on the under side of the diaphragm 80 covers only the annular surface lying outside of the valve cage 17. This difference in pressure holds the valve 18 firmly on its seat, and prevents any flow of water. When the 85 handle 44 is depressed, however, the head 41 is tilted laterally, as shown in Figure 2. The sleeve valve 29 is raised until the ports 28 are covered. The spring 38 is comparatively weak, and is not sufficient to overcome the excess of downward pressure on the diaphragm, so that during this movement the valve 18 remains closed. Just as the ports 28 are closed, the spider 30 comes in contact with the shoulder at the lower 90 end of the triangular portion of the stem 33. Further depression of the handle 44, 95 therefore, causes the relief valve 34 to rise to the position shown in dotted lines in Figure 2, while the sleeve valve 29 reaches the upper end of the cage 37. Just as soon as the relief valve 34 is opened, the water 100 above the diaphragm 11 is immediately discharged through the passageways 39, relieving all pressure from the upper surface of the diaphragm, so that the latter is raised by the pressure underneath and raises the valve 18 and cage 17. The ports 28 are still closed by the sleeve valve 29 so that there is 105 still no flow from the main supply pipe 1 into the bowl but the full pressure from the main is exerted against the under side of the diaphragm until the valve 18 and cage 110 115 are fully raised. As soon as the handle 44 is released however the sleeve valve 29 will be lowered and the ports 28 will be opened, as shown in Fig. 3. The relief valve 34 will be seated, and the tilting head 44 will resume its normal position. The flushing will then continue, while the space above the diaphragm is slowly refilled through the hollow needle 23. As soon as this refilling 120 is completed, the excess of pressure on the upper side of the diaphragm will again restore the parts to the original position, as shown in Figure 1. In case the handle 44 is depressed and not immediately released, the relief valve 34 will remain open, and the ports 28 will remain closed by the sleeve 125 130 valve 29.

It is to be particularly noted that the provision of the cage 17 and sleeve valve 29 insure the full opening of the valve 18 even when the pressure in the system is low.

5 The flushing operation will begin only when the handle 44 is released, its duration will always be the same, and the same amount of water will be discharged into the bowl.

It is also to be noted that the entire mechanism is contained within a unitary housing 3, which may be removed or installed as a unit. When it is desired to replace any of the packing, or to correct any other irregularity in its operation, it is only necessary to remove the cap 10, when the entire valve may be withdrawn from the housing, and all parts thereof examined.

Although I have illustrated and described the preferred embodiment of my invention, 20 it must be understood that many modifications and changes may be made therein without departing from the scope or spirit of the invention as set forth in the appended claims.

25 What is claimed is:

1. In a device of the character described, the combination of a housing having an inlet and an outlet, a primary valve associated with said outlet, a cage secured to said valve and slidable within the outlet and having ports which are uncovered when the valve is raised, and a sleeve valve reciprocable within the cage to open or close the ports from the inside.

35 2. In a device of the character described, the combination of a housing having an inlet and an outlet, a diaphragm extending across the space within the housing, a primary valve secured centrally to the diaphragm and adapted to seat on the mouth of said outlet, a cage secured to said valve and fitting within the outlet and having ports which are uncovered when the valve is raised, and a sleeve valve reciprocable within the cage to open or close the ports from the inside.

40 3. In a device of the character described, the combination of a housing having an inlet and an outlet, a primary valve adapted to seat on the mouth of said outlet, a cage secured to the valve and having ports which are uncovered when the valve is raised, a sleeve valve within the cage, means operable to raise the sleeve valve to close said ports from the inside and subsequently to raise the primary valve and cage, and means to lower the sleeve valve to open said ports while the cage is still raised.

45 4. In a device of the character described, the combination of a housing having an inlet and an outlet, a primary valve associated with said outlet, a cage secured to said valve and slidable within the outlet and having ports which are uncovered when the valve and cage are raised, a retaining ring

secured within the lower end of the cage, a sleeve valve within the cage, and a tilting head operable between the retaining ring and sleeve valve to raise the latter into position to close said ports.

5. In a device of the character described, the combination of a housing having an inlet and an outlet, a primary valve adapted to seat in the mouth of said outlet, a cage secured to said valve and slidable within the outlet and having ports which are uncovered when the valve and cage are raised, a retaining ring secured within the lower end of the cage, a sleeve valve reciprocable within the cage to open or close the ports from the inside, a tilting head between the retaining head and sleeve valve and operable to raise the latter to close said ports and subsequently to raise the cage and primary valve, and means to lower the sleeve valve to open said ports while the cage is still raised.

6. In a device of the character described, the combination of a housing having an inlet and an outlet, a diaphragm extending across the space within the housing, a primary valve secured centrally to the diaphragm and adapted to seat on the mouth of said outlet, a cage secured to said valve and fitting within the outlet and having ports which are uncovered when the valve and cage are raised, a retaining ring secured within the lower end of the cage, a sleeve valve within the cage, and a tilting head operable between the retaining ring and sleeve valve to raise the latter into position to close said ports.

7. In a device of the character described, the combination of a housing having an inlet and an outlet, a diaphragm extending across the space within the housing, a collar secured centrally of the diaphragm, a cage slidable within the outlet and having an upwardly extending boss secured within the collar, a primary valve clamped between the cage and collar and adapted to seat on the mouth of said outlet, said cage having ports which are uncovered when the primary valve and cage are raised, and a sleeve valve reciprocable within the cage to open and close said ports from the inside.

8. In a device of the character described, the combination of a housing having an inlet and an outlet, a diaphragm extending across the space within the housing, a collar secured centrally of the diaphragm, a cage slidable within the outlet and having an upwardly extending boss secured within the collar, a primary valve clamped between the cage and collar and adapted to seat on the mouth of said outlet, said cage having ports which are uncovered when the primary valve and cage are raised, a sleeve valve reciprocable within the cage, means operable to raise the sleeve valve to close said ports from the inside and subsequently to raise the cage and primary valve, and means

to lower the sleeve valve to open said ports while the cage is still raised.

9. In a device of the character described, the combination of a housing having an inlet and an outlet, a diaphragm extending across the space within the housing, a collar secured centrally of the diaphragm, a cage slidable within the outlet and having an upwardly extending boss secured within the collar, a primary valve clamped between the cage and collar and adapted to seat on the mouth of said outlet, said cage having ports which are uncovered when the primary valve and cage are raised, a retaining ring secured within the lower end of the cage, a sleeve valve reciprocable within the cage, a tilting head operable between the retaining ring and sleeve valve to raise the latter into position to close said ports from the inside and subsequently to raise the primary valve and cage, and spring means acting between the cage and sleeve valve to lower the latter to open said ports while the cage is still raised.

10. In a device of the character described, the combination of a housing having an inlet and an outlet, a diaphragm extending across the space within the housing, a collar secured centrally of the diaphragm, a cage slidable within the outlet and formed with an upwardly extending boss secured within the collar and having a central vertical bore therethrough, a primary valve clamped between the cage and collar and adapted to seat on the mouth of said outlet, a relief valve seating on the upper end of the boss and having a stem guided within said bore, said stem being formed so as to leave passageways through the bore when the relief valve is raised, and means for preventing the discharge of water past the primary valve during its opening movement.

11. In a device of the character described, the combination of a housing having an inlet and an outlet, a diaphragm extending across the space within the housing, a collar secured centrally of the diaphragm, a cage slidable within the outlet and formed with an upwardly extending boss secured within the collar and having a central vertical bore therethrough, a primary valve clamped between the cage and collar and adapted to seat on the mouth of said outlet, said cage having ports which are uncovered when the primary valve and cage are raised, a sleeve valve reciprocable within the cage to open and close said ports from the inside, a relief valve seating on the upper end of said boss and having a stem guided within said bore, said stem being formed so as to leave passageways through the bore when the relief valve is raised, means for raising said sleeve valve to close said ports and subsequently raise said relief valve, and means for lowering the sleeve valve to open said ports while the cage is raised.

12. In a device of the character described, the combination of a housing having an inlet and an outlet, a diaphragm extending across the space within the housing, a collar secured centrally of the diaphragm, a cage slidable within the outlet and formed with an upwardly extending boss secured within the collar and having a vertical central bore therethrough, a primary valve clamped between the cage and collar and seating on the mouth of said outlet, said cage having ports which are uncovered when the primary valve and cage are raised, a sleeve valve reciprocable within the cage to open and close said ports from the inside, a retaining ring secured within the lower end of the cage, a tilting head operable within the retaining ring and sleeve valve to raise the latter into position to close said ports, and a relief valve seating on the upper end of the boss and having a stem guided within said bore, said stem being formed so as to leave passageways through the bore when the relief valve is raised, said tilting head being operable upon further movement after the sleeve valve is closed to open said relief valve.

13. In a flush valve mechanism, the combination of a valve seat, a primary valve seating thereon and having a depending cage guided within the seat and formed with a boss extending upwardly through the valve, said boss having a central bore therethrough, a relief valve seated on said boss and having a stem guided in said bore and of less cross sectional area than the bore so as to leave a relief passageway when the relief valve is raised, means for opening the relief valve and subsequently opening the primary valve, means for preventing the discharge of water past the primary valve during its opening movement and means for returning the relief valve to its seat while the primary valve remains open.

14. In a flush valve mechanism, the combination of a valve seat, a primary valve seating thereon and having a depending cage secured thereto and guided within the seat, a diaphragm having a collar secured centrally thereof to which the cage is secured, said cage being formed with a boss extending upwardly through said valve and collar and having a central bore therethrough, a relief valve seated on said boss and having a stem guided in said bore and of less cross sectional area than the bore so as to leave a relief passageway, means for opening the relief valve and subsequently opening the primary valve, means for preventing the discharge of water past the primary valve during its opening movement and means for returning the relief valve to its seat while the primary valve remains open.

15. In a flush valve mechanism, the combination of an outlet having a mouth form-

- ing a valve seat, a primary valve seating thereon and having a depending cage guided within the mouth, a diaphragm having a collar secured centrally thereto to which the cage and primary valve are secured, said collar having a bore with a hollow needle removably held therein and furnishing a restricted communication between the spaces on opposite sides of the diaphragm, a passage 10 way between the interior of the cage and the space above the diaphragm, a relief valve controlling said passageway, means for opening the relief valve and subsequently opening the primary valve, means 15 for preventing the discharge of water past the primary valve during its opening movement and means for returning the relief valve to its seat while the primary valve remains open.
16. In a flush valve mechanism, the combination of an outlet having a mouth forming a valve seat, a primary valve seating thereon and having a depending cage guided within the mouth, a diaphragm having a 20 collar secured centrally thereof to which the cage and primary valve are secured, said collar having a bore with a hollow needle removably held therein and furnishing a restricted communication between the spaces 25 on opposite sides of the diaphragm, a peripheral flange formed on said collar below the diaphragm, said flange and primary valve having corresponding annular shoulders, a screen seated on said shoulders to 30 prevent clogging of the duct through said needle, a passageway between the interior of the cage and the space above the diaphragm, a relief valve controlling said passageway, means for opening the relief valve 35 and subsequently opening the primary valve, and means for returning the relief valve to its seat while the primary valve remains open.
17. In a flush valve mechanism, the combination of a diaphragm having a collar secured centrally thereto and formed with a peripheral flange beneath the diaphragm, a primary valve secured to the lower end of the collar in spaced relation to said flange, a bleed duct through the collar connecting the space above the diaphragm with the space 45 between the flange and primary valve, corresponding annular shoulders formed on said flange and valve outside of the duct, and a screen seated on said shoulders to prevent clogging of the duct.
18. In a flush valve mechanism, the combination of a diaphragm having a collar secured centrally thereof and formed with a peripheral flange beneath the diaphragm, a primary valve secured to the lower end 50 of the collar in spaced relation to said flange, a bore through the collar connecting the space above the diaphragm with the space 55 between the flange and primary valve, a hollow needle seated in said bore and forming a bleed duct, said needle projecting above the end of the collar, whereby it may be easily removed and replaced, annular shoulders formed on said flange and valve 60 outside of the duct, and a screen seated on said shoulders to prevent clogging of the duct.
19. In a flush valve mechanism, the combination of an outlet having a mouth forming a valve seat, a valve cooperating with said seat, a cage guided within said mouth and having a boss formed thereon and projecting upwardly through the valve, a collar secured to the boss and clamping the 65 valve to the cage, a diaphragm secured to said collar and responsive to an excess of pressure above or below to close or open the valve, means for changing the pressure to operate said valve, and means to prevent the 70 escape of any water from beneath the diaphragm into the outlet before the valve is fully open.
20. In a flush valve mechanism, the combination of an outlet having a mouth forming a valve seat, a primary valve cooperating with said seat, a cage secured in depending relation to the valve and guided for reciprocation within said mouth, said cage 75 having ports in its side walls near the top, a sleeve valve reciprocable within the cage to cover or uncover said ports, a relief valve above the primary valve and having a stem reciprocably connected to the cage, said sleeve valve being connected with said stem 80 and having a limited sliding movement longitudinally thereof.
21. In a flush valve mechanism, the combination of an outlet having a mouth forming a valve seat, a primary valve cooperating with said seat, a cage secured in depending relation to the valve and reciprocable within said mouth, said cage having 85 ports in its side walls near the top, a sleeve valve reciprocable within the cage to cover or uncover said ports, a relief valve above the primary valve and having a stem extending downwardly into the cage and slideable therein, said stem having a reduced lower end, and a spider secured to the sleeve valve and slidably mounted on the reduced portion of said stem.
22. In a flush valve mechanism, the combination of an outlet having a mouth forming a valve seat, a primary valve cooperating with said seat, a cage secured in depending relation to the valve and reciprocable within said mouth, said cage having 90 ports in its side walls near the top, a sleeve valve reciprocable within the cage to cover or uncover said ports, a relief valve above the primary valve and having a stem extending downwardly into the cage and slideable therein, means engageable with the sleeve valve to raise the same within the 95

- cage to cover said ports, and means carried by the sleeve valve to engage said stem and open the relief valve upon further upward movement of the sleeve valve.
- 5 23. In a flush valve mechanism, the combination of an outlet having a mouth forming a valve seat, a primary valve cooperating with said seat, a cage secured in depending relation to the valve and reciprocable within said mouth, said cage having ports in its side walls near the top, a sleeve valve reciprocable within the cage to cover or uncover said ports, a relief valve above the primary valve and having a stem extending 10 downwardly into the cage and slideable therein, means engageable with the sleeve valve to raise the same within the cage to cover said ports, a spider secured to the sleeve valve and slideable on the lower end of said stem, and a shoulder on said stem engageable by the spider as soon as the sleeve reaches port closing position, so that further upward movement of the sleeve valve causes the relief valve to open.
- 15 24. In a device of the character described, the combination of a housing having an inlet and an outlet, a primary valve normally closing said outlet, a diaphragm carrying said primary valve, a cage movable with 20 said primary valve and having ports, a sleeve valve reciprocable within the cage to cover and uncover said ports, a handle, and means operated by said handle to control the position of the sleeve valve.
- 25 25. In a device of the character described, the combination of a housing having an inlet and an outlet, a primary valve normally closing said outlet, a diaphragm above and carrying said primary valve, a cage connected to and movable with the primary valve, said cage having ports which are uncovered when the valve and cage are raised,
- 20 a sleeve valve in the cage to open and close said ports from the inside, a relief valve for relieving the pressure above the diaphragm, means for raising said sleeve valve to close said ports and thereafter raising the relief valve, and means for lowering said sleeve valve to open said ports while the cage is raised.
- 25 26. In a device of the character described, the combination of a housing having an inlet and an outlet, a diaphragm within the housing, a primary valve connected to the housing and normally closing said outlet, a cage connected to said primary valve and fitting within the outlet and having ports which are uncovered when the valve is raised, a sleeve valve reciprocable within the cage to open or close the ports from the 30 inside, a relief valve having a loose connection with the sleeve valve, and means for raising the sleeve valve to cover said ports and subsequently raising the relief valve to relieve the pressure above the diaphragm.
- 35 27. In a device of the character described, the combination of a housing having an inlet and an outlet, a primary valve normally closing said outlet, a diaphragm carrying said primary valve, means for establishing 30 a differential pressure on the diaphragm, a relief valve for relieving the pressure above the diaphragm, a cage carried by the primary valve and having ports which are uncovered when the primary valve is raised, 75 hand operated means for closing said ports from the inside while opening the relief valve to cause the primary valve to be raised, so that no water is discharged through said primary valve until said hand operated means is released.
- 40 In testimony that I claim the foregoing as my own, I have hereto affixed my signature.

THOMAS ROBERT BEGGS.
